Inventor:
John M. Fitzgerald
By Taylor & Brown his Atty.

UNITED STATES PATENT OFFICE.

JOHN M. FITZGERALD, OF RIVER FOREST, ILLINOIS.

REINFORCED CONCRETE CRIBBING.

Application filed October 30, 1925. Serial No. 65,728.

This invention relates to cribbing of pre-formed units, and more particularly to filler blocks used with such units.

The invention consists of the devices and combinations of devices herein illustrated and described, and more particularly pointed out in the claims appended hereto.

In the drawings:

Figure 1 illustrates, in a perspective view 10 one form of cribbing construction to which my invention is applied.

Figure 2 is a side elevation of filler blocks, spacing apart the rear ends of the anchor units of the crib.

Figure 3 is an enlarged view in perspective, of the filler block.

Figure 4 is a view similar to Figure 2, showing a modification of the anchor units.

Figure 5 is an end view, partly in section, of the modification shown in Fig. 4.

Figures 6 and 7 are side and end elevations, respectively, of another modified form of anchor units.

In said drawings, the front crib wall 25 shown in Figure 1 is composed of layers of stretcher units 13, substantially square in the body portion and provided at each end with downwardly projecting members 15, whereby the superposed layers are provided 30 with drainage spaces 19, extending longitudinally of the wall. The ends of the units 13 are shown notched or kerfed, 14, in this instance, for ready interlocking connection with the end of the header or anchor units.

35 These are provided with laterally extending flange members 11 forming a T-shaped end to interlock with the stretcher units.

There is no rear wall to the crib, the header units 10 merely extending to the rear, as 40 shown in Figure 1, and in this position they act as anchor members for the front wall when the earth or other filling material is positioned upon and between them and up 45 against the rear face of the crib front wall.

As shown in Figure 1, some of the stretchers 13 are shorter than others to provide broken or staggered joints between the 50 stretcher ends and T-shaped headers. When the joints are so staggered, there is a space 55 between the lower and upper surfaces of the T-shaped heads of the free ends of the headers in the same vertical plane. To space these ends apart, vertically, when no rear cribbing wall is used, a filler block B of a height equal to the space between the

bodies of the headers in alternate rows of cribbing units, is provided, one of which is shown detached in Figure 3. These blocks are provided upon their ends with upwardly 60 and downwardly extending flanges 25, thus forming a recess in each end, of dimensions to receive the header or anchor unit, as clearly shown. The depth of these recesses is such that the flanges embrace the sides of 65 the headers, the inside faces 26 of the flanges 25 functioning as shoulders to arrest any tendency of lateral movement or shifting of the header-anchor units.

The header units 10, shown in Figure 1, 70 are provided with downwardly extending members 12 which are of equal height as the members 15 on the stretchers, and these prevent the blocks B from being shifted rearwardly.

75 In the form shown in Figures 4 and 5, the downwardly projecting members 12 are omitted and the blocks B, positioned as before, are prevented from becoming shifted rearwardly by the contact of the ends 27 of 80 the block flanges 25, with the inside faces of the anchor flanges 11.

In some instances it is not necessary to provide specific means described for preventing the blocks from rearward movement, 85 and therefore the header or anchor units need have a T-shaped interlocking head at one end only, i. e. where the header interlocks with stretcher units to form the front wall of the crib.

90 Such a modification is indicated by Figures 6 and 7, where the rear end of the header is of the same cross-sectional area and form as the body, and where the flanges 11 and depending member 12 are entirely omitted.

95 The advantage of having the headers provided with a T-shaped head at each end is of convenience in enabling either end to be used as the interlocking member of the front 100 wall, as well as of a rear wall when used, and also of affording means for holding the blocks B from being shifted rearwardly from between the ends of the headers. The advantage of the block-separated ends of the 105 anchor members shown in Figures 6 and 7 is mainly one of saving of materials by the omission of the members 11 and 12.

110 While I have shown header and stretcher units 10 and 13 having interlocking means to form the front wall, and as to which means, per se, I am making no claims herein,

it will be manifest that header and stretcher units having other forms of interlock for a front wall may be used with a filler block to separate the rear ends of the headers when no rear crib wall is used, and when the headers proper function mainly as rearwardly extending anchor members for the front wall.

I claim as my invention:

1. An open-sided cellular cribbing structure of pre-formed, reinforced concrete units, comprising the combination of superposed header units, each having a T-shaped end, and superposed stretcher units adapted for interlocking engagement with the T-shaped header end to form a cribbing wall, the spaced free ends of said header units extending at substantially right angles to said wall, and a spacer block provided on each end with vertically extending flanges adapted for contact with the sides of the spaced header units adjacent their free ends to keep the wall in vertical alignment.
2. In an open-sided cellular cribbing structure the combination with a plurality of stretcher members, a plurality of transversely extending header members, each header member having a T-shaped end adapted for interlocking connection with the stretcher ends to form a cribbing wall, the header units forming transversely extending, spaced-apart walls, with the ends of the headers free, a spacer block located between the free ends of the header units and having spaced apart flanges on its ends adapted for engagement with the sides of the header units to prevent lateral movement between the block and said units and preserve the vertical alignment of the transversely extending wall, the stretchers, headers and blocks being preformed units of reinforced concrete.

3. An open-sided cellular cribbing of pre-formed, reinforced concrete units, comprising a plurality of superposed stretcher units and header units, each header having a T-shaped end to interlockingly engage the 45 stretcher ends to form a retaining wall, the headers being superposed to form a plurality of spaced-apart brace walls extending transversely of the retaining wall, the free ends of the header units being spaced apart by 50 spacer blocks, and means to prevent the lateral movement of the header ends and the blocks to preserve the vertical alignment of the headers in each transverse wall.

4. An open-sided cellular cribbing structure of pre-formed reenforced concret units, comprising the combination of superposed header units having T-shaped ends, and superposed stretcher units adapted for interlocking engagement with one of the ends of 55 the T-shaped headers to form a cribbing wall, and a filler block of a height to fit between the bodies of headers in alternate rows 60 of cribbing units, arranged between the free ends of said headers.

5. An open-sided cellular cribbing structure of pre-formed reenforced concret units, comprising the combination of superposed header units each having a T-shaped end, and superposed stretcher units adapted for 65 interlocking engagement with the T-shaped header end to form a cribbing wall, and a filler block of a height equal to the distance 70 between the bodies of adjacent headers, arranged between the free ends of said headers.

In testimony, that I, claim the foregoing as my invention, I affix my signature, this 28th day of October, 1925.

JOHN M. FITZGERALD.
